(57) **CLAIM**

The ornamental design for a telecommunications gateway, as shown and described.

DESCRIPTION

1. Telecommunications gateway

1.1 : Perspective

1.2 : Front

1.3 : Back

1.4 : Left

1.5 : Right

1.6 : Top

1.7 : Bottom

The present ornamental design is a combination of the shape and pattern of a “telecommunications gateway” as shown and described.

The broken line shown are included for the purpose of illustrating portions of the telecommunications gateway that forms no part of the claimed design.
